RAILWAY TRAFFIC CONTROLLING
APPARATUS

Henry S. Young, Wilkinsburg, and Ronald A. McCann, Swissvale, Pa., assignors to The Union Switch & Signal Company, Swissvale, Pa., a corporation of Pennsylvania

Application December 14, 1935, Serial No. 54,430

6 Claims. (Cl. 246—3)

Our invention relates to railway traffic controlling apparatus, and more particularly to apparatus involving the control of signals arranged between passing sidings of a single track stretch 5 of railway.

An object of the invention is to provide means for preventing an operator from setting at stop the signals for governing traffic movements in a given direction through a single track stretch, if 10 the operator should erroneously attempt to clear an opposing signal while the signals for the given direction are indicating caution or proceed. Another object of the invention is to provide means for preventing the automatic clearance of an intermediate signal governing traffic movements in a given direction, when an opposing signal at one 15 end of the stretch has been cleared and is returned to stop as a result of a train over-running a signal governing traffic movements in the given direction at the other end of the stretch. 20

The apparatus of our invention is an improvement over that disclosed in the copending applications Serial No. 125,659 filed July 29, 1926, by H. A. Wallace, for Railway traffic controlling apparatus; Serial No. 313,772 filed October 20, 1928, by H. A. Thompson, for Multiple control apparatus; Serial No. 379,163 filed July 18, 1929, by C. A. Brooks, for Multiple control apparatus; and Serial No. 505,328 filed Dec. 29, 1930, by E. M. Allen, 25 C. A. Brooks and H. A. Thompson, for Railway traffic controlling apparatus.

We will describe two forms of apparatus embodying our invention, and will then point out the novel features thereof in claims.

In the accompanying drawings, Figs. 1 to 3, inclusive, when placed end to end from left to right in the order named, constitute a diagrammatic view showing one form of apparatus embodying our invention, while Figs. 1^a and 3^a show 35 apparatus and circuits which may be used in conjunction with Figs. 1, 2 and 3 to illustrate an alternative form of the invention.

Similar reference characters refer to similar parts in each of the views.

The invention, as illustrated, is applied to a stretch of single track railway X extending eastward from a passing siding P2, shown at the left-hand end of Fig. 1, to a passing siding P7, shown 40 at the right-hand end of Fig. 3.

By means of insulated rail joints, designated by the reference character 3, the traffic rails of the stretch, designated by the reference characters 1 and 1^a, respectively, are divided into track sections 1T to 8T, inclusive, with only the west end 45 of section 8T and the east end of section 1T

shown. Sections 2T and 7T include track switches 2 and 7 of the associated sidings P2 and P7, respectively. Each track section is provided with a track circuit, including a battery designated by the reference character 6 and a track relay designated by the reference character R with a prefix designating the section to which it belongs. 5

The signals may be of any suitable type, but for the purposes of this disclosure color light signals have been used. The signals shown in Fig. 1, 10 designated RA2 and RB2, respectively, govern eastbound traffic movements over switch 2 in its normal and reverse positions, respectively; while the signals designated LA2 and LB2 govern westbound traffic movements over switch 2 in its normal and reverse positions, respectively. 15

The reference characters R2HS and L2HS designate a pair of directional relays which may be controlled from a remote point in any satisfactory manner to control traffic movements over switch 20 2 when traffic conditions are favorable, as indicated by the energized condition of the home relays, herein designated R2H and L2H, respectively. The controlling circuits for relays R2HS and L2HS form no part of our present invention, but 25 they may, for example, be controlled by manual operation of suitable circuit controllers at a remote point, such as a train dispatcher's office.

Relay R2HS controls a slow releasing signal 30 control relay RA2HP or RB2HP in the signal network, depending on the position of switch 2 indicated by the associated switch position repeating or indicating relay 2KR, to govern eastbound traffic movements over switch 2. In a similar manner, relay L2HS controls signal control 35 relays LA2HP and LB2HP to govern westbound traffic movements over switch 2.

In the accompanying drawings, the contacts of each relay are generally shown directly under their relay, but in each case where this is not done, the contact is connected with the relay by a dashed line or is labeled with its relay designation and with a numerical suffix.

The source of current employed has been diagrammatically illustrated in Fig. 2 as a battery 45 having a center tap designated as terminal C, and positive and negative terminals designated B and N, respectively. It should be understood that while only one source of current has been illustrated, separate sources, such as the one shown for example, may be provided at the ends of the stretch and at the intermediate signal location, in which case the center tap of each source would be connected to a common line wire. 50

Referring again to Fig. 1, the reference char- 55

acters R²MR and L²MR designate approach locking relays for eastbound and westbound traffic movements, respectively, over switch 2. It should be understood that, although not shown in the drawings, the switch machine for switch 2 is controlled by these approach locking relays in the usual manner, so that switch 2 can not be operated with either relay R²MR or L²MR released. Approach locking relay R²MR is also herein employed to prevent the automatic clearance of an intermediate signal under dangerous traffic conditions, as will subsequently be explained.

Relay R²MR is normally held energized, both a pickup and a stick circuit for this relay being normally closed. The normally closed pickup circuit for relay R²MR passes from terminal B, through contacts 27 and 47 of relays RA2HP and RB2HP, respectively, neutral front contact 48 and normal polar contact 49 of relay 2KR, contact 45 of relay R²AR, contact R2HS¹, and the winding of relay R²MR to terminal C. The stick circuit passes from terminal B, through back contacts 27 and 47 of relays RA2HP and RB2HP, respectively, conductors 30a, 30b and 30c, the front point of contact 28 of relay R²MR, and the winding of relay R²MR to terminal C.

Relay L²MR is similarly normally held energized. Its stick circuit passes from terminal B, through back contacts 58 and 59 of relays LA2HP and LB2HP, respectively, the front point of contact 61 of relay L²MR, and the winding of relay L²MR to terminal C. The pickup circuit for relay L²MR which is also normally closed is similar to the stick circuit except that it includes front contact 68 of an approach relay L²AR instead of contact 61 of relay L²MR.

A second approach relay, designated R²AR, is also provided. Relay R²AR is normally energized over a circuit including front contact 4TR², while relay L²AR is normally energized over a circuit passing from terminal B, through front contacts 31 and 32 of track relays 5TR and 4TR, respectively, wire LW5, the winding of relay L²AR, and front contact 9 of track relay 3TR to terminal C. The reference character 2TE designates a time element relay of a commonly employed type, provided with contacts 92 and 94 which are closed a predetermined time interval after the relay is energized, to govern the release of approach locking relays R²MR and L²MR, respectively, and also having a contact 15 included in the signal control circuit network.

Relay L²H is normally energized by a circuit which is controlled by contact 4TR¹. As indicated by the dash line between terminal B and contact 4TR¹, relay L²H may also be controlled by other means such, for example, as traffic conditions for the stretch of track west of section 1T.

Relay R²H is normally energized by current of normal polarity passing from terminal B, through the front point of contact 5HP¹, contacts 5H¹ and 4S¹, contact 55 of relay 4TR, conductor LW1, contact 3TR¹, and the winding of relay R²H to terminal C.

As shown in Fig. 1, switch 2 is in its normal position. With switch 2 in its normal position, pole-changer 9, which is controlled by switch 2, is in its normal position, and relay 2KR is therefore energized by current of normal polarity. The front contacts of relay 2KR are therefore closed, and its normal polar contacts are also closed.

Relays RA2HP and RB2HP are normally deenergized. Red lamp R of signal RA2 is therefore lighted by a circuit including the back point of contact 28 of relay RA2HP, and red lamp R of

signal RB2 is lighted by a circuit including the back point of contact 69 of relay RB2HP.

In Fig. 2, the intermediate portion of track X is provided with intermediate signals 4 and 5 for governing the movement of westbound and eastbound traffic, respectively. These signals and associated directional stick relays designated 4S and 5S, are controlled by the signal control relays which are designated H and HP, respectively, with a prefix corresponding to their associated signal. For example, signal 4 is controlled by relay 4H and by the slow pickup and slow release repeater relay 4HP. Relay 4H is normally energized by current of reverse polarity over a circuit passing from terminal N, through the back point of contact 21 of relay LA2HP in Fig. 1, front contacts 22 and 23 of track relays 3TR and 2TR, respectively, back contacts 24 and 25 of relays RB2HP and RA2HP, respectively, conductor J2, front contact R2MR¹, wire LW3, front contact 26 of relay 4TR, and the winding of relay 4H to terminal C. Relay 4HP is normally energized over a circuit including front contact 29 of relay 4H.

With relay 4H energized by current of reverse polarity and with relay 4HP energized, lamp Y of signal 4 is lighted by a circuit passing from terminal B, through the front point of contact 38 of relay 4HP, contact 39 of relay 4H in its reverse position, and lamp Y of signal 4 to terminal C.

Referring now to Fig. 3, the signals RA7, RB7, LA7 and LB7 are identical to the similarly located signals at the opposite end of the stretch of track X, and the apparatus and circuits of Fig. 3 control the signals therein in the same manner as the signals of Fig. 1 are controlled. The wires LW2, LW4 and LW6 extending between Figs. 2 and 3 are included in circuits which are equivalent to those passing over wires LW1, LW3 and LW5, respectively.

In order to further describe the invention, it will first be assumed that the circuits and apparatus are in their normal condition, as shown, and that an operator proceeds to clear signals RA2 and RA7 for directing an eastbound train through the stretch, by picking up directional control relays R2HS and R1HS, respectively.

When relay R2HS picks up, the front point of its contact 16 completes a circuit for relay RA2HP, passing from terminal B, through back contacts 11, 12 and 13 of relays LA2HP, LB2HP and L2HS, respectively, (checking that the L² signals are at stop), front contact 14 of track relay 2TR, back contact 15 of relay 2TE, the front point of contact 16 of relay R2HS, front contact 17 of relay R2H, the front neutral and normal polar contacts 18 and 19, respectively, of switch position repeating relay 2KR, and the winding of relay RA2HP to terminal C. Relay RA2HP accordingly picks up and at the back point of its contact 20, opens the circuit for the R lamp of signal RA2 and at the front point of this contact, closes the circuit, including contacts 88 and 70 of relay R2H, for the G lamp of this signal, thereby changing the indication of signal RA2 from stop to proceed. Relay RA2HP also, at back contact 25, opens the circuit for relay 4H, and at back contact 27, opens the pickup and stick circuits previously traced for approach locking relay R²MR. When relay R²MR releases, its front contact R2MR¹ opens another point in the circuit for relay 4H, and contact 28 closes its back point in an operating circuit for time element relay 2TE.

When relay 4H releases, its front contact 29

opens the circuit for slow-acting relay 4HP, and its front contact 4H1 opens the circuit for relay L7H passing from terminal B, through front contacts 4HP1 and 4H1, back contact 5S1, front contact 5 tact 34 of track relay 5TR, wire LW2, front contact 6TR1, and the winding of relay L7H to terminal C.

When relay L7H releases, it opens at front contact 31, a common point in the operating circuits 10 for relays LA7HP and LB7HP, thereby insuring that signals LA7 and LB7 will continue to display the stop indication irrespective of the condition of the operator controlled directional relay L7HS.

When relay 4HP releases, the front point of 15 contact 38 opens the circuit for the Y lamp of signal 4, and the back point of this contact closes the circuit for the R lamp of this signal, so that the indication of signal 4 changes from caution to stop. Relay 4HP also, at the front point of contact 20 tact 4HP1, disconnects the operating circuit for relay L7H from terminal B, and connects this circuit to terminal N at the back point of the same contact.

When relay R7HS is picked up to clear the leaving signal RA7 for the traffic movement under consideration, it opens another point in the operating circuits for relays LA7HP and LB7HP at the back point of contact 41. Relay R7HS, at the front point of contact 41, completes a circuit 30 for relay RA7HP or RB7HP, depending on the position of switch 7 through its switch position repeating relay 7KR. With switch 7 and relay 7KR in their normal position, as shown, the circuit includes relay RA7HP, and is similar to that 35 for relay RA2HP at the other end of the stretch. When relay RA7HP picks up, the indication of signal RA7 is changed from stop to proceed in the same manner as the indication of signal RA2 was changed when relay RA2HP picked up.

40 Relay RA7HP also, at the back point of contact 42, disconnects terminal N from the circuit for relay 5H, which is similar to the circuit previously traced for relay 4H, and, at the front point of this contact, connects terminal B to the same circuit. Relay 5H accordingly moves its polar contact 43 from the reverse position, in which it is shown, to the normal position, thereby opening the circuit for the Y lamp of signal 5, which is similar to the circuit traced for the corresponding lamp of signal 4, and closing the circuit for the G lamp thereof, so that the indication of signal 5 changes from caution to proceed.

Relay RA7HP also, at back contact 76, opens a common point in the pickup and stick circuits for 55 relay R7MR, which are similar to the circuits previously traced for relay L2MR, and relay R7MR accordingly releases to prevent movement of switch 7 while an associated signal is displaying a proceed indication.

60 If now a train enters section 2T, track relay 2TR releases and, at front contact 14, opens the circuit for relay RA2HP, so that this relay will release and thus cause the extinguishing of the G lamp and the lighting of the R lamp of signal RA2, thereby changing the indication of signal 65 RA2 from proceed to stop while section 2T is occupied, irrespective of the condition of relay R2HS. Track relay 2TR, in releasing, also opens a point in the circuit for relay 4H at front contact 23, to prevent the closure of this circuit 70 when relay R2MR picks up.

Relay 2TR also closes a pickup circuit for relay R2MR, providing the operator has released relay R2HS following the entry of the train into 75 section 2T. This circuit passes from terminal B,

through back contacts 27 and 47 of relays RA2HP and RB2HP, respectively, conductor 30a, contacts 36 and R2HS1 of relays 2TR and R2HS, respectively, and the winding of relay R2MR to terminal C.

It may be observed at this time that front contacts 23, 22 and 26 of relays 2TR, 3TR and 4TR, respectively, of sections 2T-4T are included in the circuit for relay 4H, and therefore relay 4H will be unable to pick up and effect clearance of signal 4 until after the train has vacated all of these sections.

When the train enters section 3T, relay 3TR releases, and opens the circuit for approach relay L2AR at front contact 8. Relay L2AR then releases and, at its front contact 60, opens the pickup circuit previously traced for relay L2MR, without effect however at this time as the stick circuit for relay L2MR has not been interrupted.

When the train enters section 4T, relay 4TR releases, and opens a further point in the circuit for relay L2AR at front contact 32, and also opens the circuit for approach relay R7AR at front contact 62. Relay R7AR accordingly releases and, at its front contact 64, opens another point 25 in a pickup circuit for relay R7MR.

When the train enters section 5T, relay 5TR releases and, at its several contacts, makes circuit changes corresponding to those made upon the release of relay 4TR. Relay 5H, however, 30 which has been energized up to this time, now releases, and opens a further point in the circuit for relay R2H at front contact 5H1, and opens the circuit for its slow-acting repeating relay 5HP at front contact 36.

Before relay 5HP releases, however, a pickup circuit is completed for stick relay 5S, passing from terminal B, through back contact 66 of relay 5TR, the front point of contact 67 of relay 5HP, and the winding of relay 5S to terminal C. Stick relay 5S now picks up and opens a further point in the circuit for relay L7H at back contact 5S1; at front contact 5S2, closes a path around front contact 5H1, so that a circuit for relay R2H can be completed as soon as the train vacates section 4T; and closes front contact 68 in its own stick circuit.

An instant later, relay 5HP releases, and opens the pickup circuit for relay 5S at the front point of contact 67, and, at the back point of this contact, completes the stick circuit for relay 5S, passing from terminal B, through the back point of contact 67, contact 68 of relay 5S, and the winding of relay 5S to terminal C. Relay 5HP also disconnects terminal B from the circuit for relay R2H at the front point of contact 5H1 and, at the back point of this contact, connects this circuit to terminal N.

When the train vacates section 4T, and relay 4TR picks up, a circuit for relay R2H including contact 5S2 and the back point of contact 5H1, is established by the closure of front contact 55 of relay 4TR, but since the direction of current flow has been reversed at contact 5H1, the polar contacts 70 and 71 of relay R2H move to their reverse position. If relay R2HS is closed, the circuit for relay RA2HP will now again be established by the closure of front contact 17 of relay R2H, and the circuit for the R lamp of signal RA2 will accordingly be opened, and that of the Y lamp thereof closed through contact 70 of relay R2H in its reverse position, so the indication of signal RA2 will change from stop to caution.

As the train advances into section 6T, track 75

relay 6TR releases, and opens a further point in the circuit for relay L7H at front contact 6TR1. Relay 6TR also opens a further point in the circuit for relay 5H at front contact 74; and maintains the circuit for relay R7AR open at front contact 75, so that neither of the relays 5H and R7AR will be able to pick up until after the train vacates section 6T.

When the train enters section 7T, relay 7TR releases, and opens the circuit for relay RA7HP at front contact 77. Relay 7TR also opens a point in the circuit for relay 7TE at front contact 78 to prevent a circuit being completed for relay TE upon the closure of back contact 76 of relay 10 RA7HP an instant later. Relay 7TR also prepares a pickup circuit for relay R7MR at back contact 82 by closing a path around front contact 64 of relay R7AR.

An instant after relay 7TR releases, relay 20 RA7HP releases, and opens the circuit for the G lamp of signal RA7, and completes the circuit for the R lamp of this signal, so that its indication changes from proceed to stop.

Relay RA7HP also completes the pickup circuit prepared for relay R7MR, by the closure of back contact 76. This pickup circuit passes from terminal B, through contacts 81 and 76 of relays RB7HP and RA7HP, respectively, contact 82 of relay 25 7TR, and winding of relay R7MR to terminal C.

When relay R7MR picks up, the back point of its contact 98 opens another point in the circuit for relay 7TE, to prevent the energization of relay TE upon closure of front contact 78 of relay 7TR 35 as the train vacates section 7T. Relay R7MR also re-establishes its own stick circuit at the front point of contact 98.

When the train vacates section 6T, relay 6TR picks up and recloses the circuit for relay R7AR at front contact 75. Relay R7AR accordingly picks up, and recloses the initial pickup circuit for relay R7MR at front contact 64 which circuit passes from terminal B, through back contacts 81 and 76 of relays RB7HP and RA7HP, respectively, front contact 64 of relay R7AR, and the winding of relay R7MR to terminal C.

When the train enters section 8T, relay 8TR releases, and opens the pickup circuit for relay L7AR at front contact 8TR2. Relay L7AR in turn releases and, at front contact 93, opens the normally closed pickup circuit for relay L7MR, but without effect at this time as the stick circuit for relay L7MR has not been opened.

As the train vacates section 7T, relay 7TR again picks up, and recloses the circuit for relay 5H at front contact 84. Relay 5H then picks up, and in turn closes the circuit for relay 5HP. When relay 5HP picks up, it opens the circuit for stick relay 5S at the back point of contact 67, and relay 5S accordingly releases.

After the train vacates section 8T, track relay 8TR again picks up, and recloses the control circuit for relay L7AR which, in turn, recloses the normally closed pick-up circuit for relay L7MR.

If, after signal RA2 or RB2 and signal RA7 or RB7 have been cleared, the operator erroneously picks up relay L7HS, relay RA7HP will be de-energized by the opening of contact 95 of relay L7HS at its back point, causing signal RA7 to now indicate stop and causing signal 5 to indicate caution, and the storage of the clearance of one of the opposing signals LA7 or LB7 will also result, depending on the position of switch 1. Signal RA2 will continue to indicate proceed. When

relay L7HS picks up, the front point of its contact 95 cannot complete a circuit for either of the signal control relays LA7HP or LB7HP, since their operating circuits are open at the back point of contact 41 of relay R7HS, and also at front contact 37 of relay L7H if the eastbound train has not passed beyond section 6T. It will be observed that the opening of back contact L7HS1 is without effect at this time, as the stick circuit for relay L7MR has not been opened. Since relay L7MR is not released, its front contact L7MR1, in the circuit for relay 5H, is not opened at this time.

When the train enters section 7T, relay 7TR again picks up and, at its front contact 84, closes the circuit for relay 5H, irrespective of the condition of relay L7HS. Relay 5H accordingly picks up and, by picking up relay 5HP, effects the release of stick relay 5S. The latter relay, on releasing, closes its back contact 5S1 in the circuit for relay L7H, which accordingly picks up and enables signal LA7 to be cleared if the operator has deenergized relays R2HS and R7HS.

If, after signal RA2 or RB2 and signal RA7 or RB7 have been cleared, a train moving toward the left over-runs signal LA7 or LB7 at stop, relay 25 7TR releases and opens the circuit for relay 5H at its front contact 84, thereby causing the release of relays 5H and 5HP at the intermediate signal location, and of relays R2H and RA2HP or RB2HP at the west end of the stretch. The indication of signal RA2 or RB2 and of signal 5 accordingly changes from proceed to stop. Signal 4 will also continue to display its stop indication, on account of relay R2MR being deenergized.

With relays R2MR, RA2HP and RB2HP released, a circuit for time element relay 2TE is completed, passing from terminal B, through back contacts 27 and 47 of relays RA2HP and RB2HP, respectively, conductors 30a, 30b and 30c, back point of contact 28 of relay R2MR, front contact 51 of relay 2TR, and the winding of relay 2TE to terminal C.

The operator can now energize relay 4H by releasing relay R2HS. With relay R2HS released and approach section 1T unoccupied, relay R2MR immediately picks up over the pickup circuit first traced for this relay, through contact 45 of relay R2AR. If, however, section 1T is occupied, relay R2MR will not pick up until relay 2TE closes its contact 92 and thereby completes a third pickup circuit for relay R2MR, passing from terminal B, through contacts 27 and 47 of relays RA2HP and RB2HP, respectively, conductors 30a and 30b, contact 92 of relay 2TE, contact R2HS1, and the winding of relay R2MR to terminal C.

Relay R2MR, upon picking up, opens the circuit for relay 2TE at the back point of contact 28, and again completes the circuit for relay 4H at its front contact R2MR1. Relay 4H accordingly picks up to effect a change in indication of signal 4 from stop to proceed or from stop to caution according as relay LA2HP is energized or de-energized.

The alternative form of our invention involves the use of an HS repeating relay at each end of the stretch. These relays and their energizing circuits are illustrated in Figs. 1a and 3a, and are designated R2HSP and L7HSP, respectively. Accompanying changes in the circuits comprise the use of conductors J1 and J3, shown by dash lines, instead of contacts R2HS1 and L7HS1 of relays

R2HS and L7HS, respectively, in the circuits for relays R2MR and L7MR, and the use of contacts R2HSP1 and L7HSP1, also shown by dash lines, instead of conductors J2 and J4, respectively.

5 In this form of the invention, when relay R2HS is picked up, its front contact R2HS2 closes a circuit for relay R2HSP, only if front contact R2H1 is closed. Back contact R2HSP1 functions in a similar capacity to that of back contact R2HS1 in the first described form of the invention, in that it prevents signal 4 from being cleared until after relay R2HS has been released.

To explain the operation more fully, it will be assumed that signals RA2 and RA1 have been cleared and that the operator inadvertently picks up relay L7HS. When relay L7HS is picked up, its front contact L7HS2 closes, but since front contact L7H1 is open, relay L7HSP cannot pick up and therefore cannot open its contact L7HSP1 to open the circuit for relay 5H. Hence, although signal RA1 will now indicate stop, signal 5 will indicate caution, and signal RA2 will continue to indicate proceed.

25 If signal RA2 is cleared for an eastbound traffic movement, and if a westbound train over-runs signal LA1 at stop, track relay 7TR will release and cause the indication of signal RA2 and of signal 5 to change from proceed or caution to stop in the manner already described. In this form of the invention, since the pickup circuit for relay R2MR does not include a back contact of relay R2HS, relay R2MR will pick up at once if approach section 1T is unoccupied, or alternatively as soon as time element relay 2TE has fully operated, if section 1T is at the time occupied. However, before signal 4 can be cleared, back contact R2HSP1 must be closed. The operator must therefore release relay R2HS, and break the stick circuit for relay R2HSP at contact R2HS2 to effect the release of relay R2HSP, in order to clear signal 4.

Since the circuits and apparatus for directing westbound traffic movements over the stretch, irrespective of the form of the invention employed, are identical to those already described, their control and operation will be fully understood without further explanation.

Although we have herein shown and described only two forms of apparatus embodying our invention, it is understood that various changes and modifications may be made therein within the scope of the appended claims without departing from the spirit and scope of our invention.

55 Having thus described our invention, what we claim is:

1. In a railway signaling system, a stretch of single track railway having a passing siding and an associated switch at one end thereof, signals for governing the movement of traffic into the stretch over said switch in its normal and reverse positions respectively, control relays for said signals, an approach locking relay for said switch, a remotely controlled directional relay having a front contact included in a circuit including one or the other of said control relays according as the switch is in its normal or its reverse position, an opposing signal for governing traffic movements toward the siding and controlled by a line relay with an energizing circuit including a front contact of said approach locking relay, a pickup circuit for said approach locking relay including back contacts of said remotely controlled and said control relays respectively, and a stick circuit for said approach locking relay similar to said pickup

circuit but not including the back contact of said remotely controlled relay.

2. In a railway signaling system, a stretch of single track having a passing siding and an associated switch at one end thereof, signals for governing the movement of traffic into the stretch over the switch in its normal and reverse positions respectively, control relays for said signals, a remotely controlled relay having a front contact included in a circuit including one or the other of said control relays according as the switch is in its normal or its reverse position, a normally energized line relay for said signals controlled by traffic conditions in said stretch, a repeating relay for said remotely controlled relay, an opposing signal for governing traffic movements toward the siding and controlled by a line relay with an energizing circuit including a back contact of said repeating relay, a pickup circuit for said repeating relay including front contacts of the first specified line relay and of the remotely controlled relay respectively, and a stick circuit for said repeating relay including a front contact of said remotely controlled relay.

3. In combination, a stretch of single track railway, a first and a second as well as a third and a fourth signal spaced along said stretch in the order named with the first and second and third signals governing traffic movements in a given direction over said stretch and the fourth signal governing traffic movements in the opposite direction over said stretch, a first and a second and a third manually operable device, a circuit controlled by said first and third manually operable devices for controlling said first signal to display a more favorable indication than stop if said first manually operable device is operated while said third manually operable device is in its normal condition, a second circuit by which said second signal is normally maintained in condition to display a more favorable indication than stop, a third circuit controlled by said second and third manually operable devices for controlling said third signal to display a more favorable indication than stop if said second manually operable device is operated while said third manually operable device is in its normal condition, a fourth circuit controlled by said first and second and third manually operable devices for controlling said second signal to indicate stop and said fourth signal to display a more favorable indication than stop if said third manually operable device is operated while said first and second manually operable devices are in their normal condition, and means controlled by said first manually operable device when in condition to control said first signal to display a more favorable indication than stop for preventing operation of said third manually operable device from changing the indication of said second signal to stop.

4. In combination, a stretch of single track railway, a signal adjacent a given end of said stretch for governing traffic movements in a given direction into said stretch, a second signal adjacent the second end of said stretch for governing traffic movements in an opposite direction into said stretch, a third and a fourth signal located between the ends of said stretch for governing traffic movements in said given direction and the opposite direction respectively, a manually controlled relay for said first signal, a second manually controlled relay for said second signal, an approach locking relay associated with said first signal, a second approach locking relay associ-

ated with said second signal, a control circuit for said third signal including a front contact of said second approach locking relay and closed only if the track is unoccupied between said second and third signals, a control relay for said first signal, an energizing circuit for said control relay controlled by traffic conditions between said first and third signals and closed only if the control circuit for said third signal is closed, 10 a control circuit for said fourth signal including a front contact of said first approach locking relay and closed only under favorable traffic conditions between said first and fourth signals, a second control relay for said second signal, an 15 energizing circuit for said second control relay controlled by traffic conditions between said second and fourth signals and closed only if the control circuit for said fourth signal is closed, a pick-up and a stick circuit for said first approach locking relay one of which is closed through a back contact of said first manually controlled relay and the other of which is closed only while said first signal is controlled to indicate stop, a pick-up and a stick circuit for said 20 second approach locking relay one of which is closed through a back contact of said second manually controlled relay and the other of which is closed only while said second signal is controlled to indicate stop, a circuit controlled by a front contact of said first manually controlled relay and by a front contact of the first control relay for controlling said first signal to display a more favorable indication than stop, and a circuit controlled by a front contact of said second manually controlled relay and by a front contact of said second control relay for controlling said second signal to display a more favorable indication than stop.

5. In combination, a stretch of railway track, 40 a signal for governing traffic movements in a given direction over said stretch, a second signal for governing traffic movements in the opposite direction over said stretch, a manually controlled relay, a control relay for said first signal con-

trolled by track circuit conditions in said stretch, an approach locking relay associated with said first signal, a pick-up and stick circuit for said approach locking relay one of which is controlled by traffic conditions in said stretch and the other 5 of which is closed only while said first signal is controlled to indicate stop, means controlled by a front contact of said manually controlled relay and by a front contact of said control relay for controlling said first signal to display a more 10 favorable indication than stop, a stick relay, a pick-up and a stick circuit for said stick relay one of which is controlled by a front contact of said control relay and by a front contact of said manually controlled relay and the other of 15 which is controlled by a front contact of said manually controlled relay, and a circuit controlled by a back contact of said stick relay and by a front contact of said approach locking relay for controlling said second signal to display a 20 more favorable indication than stop.

6. In combination, a stretch of railway track, a signal for governing traffic movements in a given direction over said stretch, a second signal for governing traffic movements in the opposite 25 direction over said stretch, a manually controlled relay, a control relay for said first signal controlled by track circuit conditions in said stretch, means controlled by a front contact of said manually controlled relay and by a front contact of 30 said control relay for controlling said first signal to display a more favorable indication than stop, a stick relay, a pick-up and a stick circuit for said stick relay one of which is controlled by a front contact of said control relay and by a front 35 contact of said manually controlled relay and the other of which is controlled by a front contact of said manually controlled relay, and a circuit controlled by a back contact of said stick relay for controlling said second signal to display a 40 more favorable indication than stop.
